US00D709129S

(12) **United States Design Patent**
Moertl

(10) **Patent No.:** **US D709,129 S**
(45) **Date of Patent:** **** Jul. 15, 2014**

(54) **DISPENSER**

(71) Applicant: **Glue Dots International, LLC**,
Germantown, WI (US)

(72) Inventor: **Reid C. Moertl**, Wauwatosa, WI (US)

(73) Assignee: **Glue Dots International, LLC**,
Germantown, WI (US)

(**) Term: **14 Years**

(21) Appl. No.: **29/481,944**

(22) Filed: **Feb. 12, 2014**

Related U.S. Application Data

(62) Division of application No. 29/406,834, filed on Nov. 18, 2011.

(51) **LOC (10) Cl.** **19-02**

(52) **U.S. Cl.**

USPC **D19/69**

(58) **Field of Classification Search**

(57) **CLAIM**

The ornamental design for a dispenser, as shown and described.

DESCRIPTION

FIG. 1 is an isometric view of an embodiment of the claimed design;

FIG. 2 is a front view of the claimed design of FIG. 1;

FIG. 3 is a back view of the claimed design of FIGS. 1 and 2;

FIG. 4 is right side view of the claimed design of FIGS. 1-3;

FIG. 5 is a left side view of the claimed design of FIGS. 1-4;

FIG. 6 is a top view of the claimed design of FIGS. 1-5;

FIG. 7 is a bottom view of the claimed design of FIGS. 1-6;

FIG. 8 is an isometric view of a second embodiment of the claimed design;

FIG. 9 is a front view of the claimed design of FIG. 8;

FIG. 10 is a back view of the claimed design of FIGS. 8 and 9;

FIG. 11 is a right side view of the claimed design of FIGS. 8-10;

FIG. 12 is a left side view of the claimed design of FIGS. 8-11;

FIG. 13 is a top view of the claimed design of FIGS. 8-12;

FIG. 14 is a bottom view of the claimed design of FIGS. 8-13;

FIG. 15 is an isometric view of a third embodiment of the claimed design;

FIG. 16 is a front view of the claimed design of FIG. 15;

FIG. 17 is a back view of the claimed design of FIGS. 15 and 16;

FIG. 18 is a right side view of the claimed design of FIGS. 15-17;

FIG. 19 is a left side view of the claimed design of FIGS. 15-18;

FIG. 20 is a top view of the claimed design of FIGS. 15-19; and,

FIG. 21 is a bottom view of the claimed design of FIGS. 15-20.

The ornamental design which is claimed is shown in solid lines in the drawings. The dot-dash lines in FIGS. 1-21 define boundaries of the claimed design and form no part thereof. The other broken lines and unshaded surfaces in the drawings are for illustrative purposes only and form no part of the claimed design.

1 Claim, 9 Drawing Sheets
